 LLP

(57) **CLAIM**

The ornamental design for a ceiling lamp, as shown and described.

DESCRIPTION

1.1 is a bottom perspective view of a ceiling lamp, showing my new design;

1.2 is a left view thereof;

1.3 is a right view thereof;

1.4 is a front view thereof;

1.5 is a back view thereof;

1.6 is top view thereof; and

1.7 is a bottom view thereof.

The broken lines shown in the drawings of the ceiling lamp form no part of the claimed design.

1 Claim, 7 Drawing Sheets
